[57] CLAIM

The ornamental design for a bidet, as shown and de-
scribed.

DESCRIPTION

FIG. 1 is a perspective view taken from the top, front
and right side of a bidet showing my new design;

FIG. 2 is a left side elevational view thereof;

FIG. 3 is a top plan view thereof; and

FIG. 4 is a front elevational view thereof.

The broken line representations of openings for conven-
tional plumbing fittings in FIGS. 1 and 3 are for pur-
poses of illustration only.
